UNITED STATES PATENT OFFICE.

JULIAN N. WALTON, OF BROOKLYN, NEW YORK.

VACUUM SYSTEM.

1,112,872.

Specification of Letters Patent.

Patented Oct. 6, 1914.

Application filed December 8, 1913. Serial No. 805,271.

To all whom it may concern:

Be it known that I, JULIAN N. WALTON, a citizen of the United States, residing at Brooklyn, in the county of Kings and State 5 of New York, have invented new and useful Improvements in Vacuum Systems, of which the following is a specification.

The present invention relates to vacuum cleaner systems and the like, and more particularly to novel means for creating a vacuum, said means incidentally constituting mechanism for carrying off the dust-laden air received by the system.

An embodiment of the invention that is 15 considered the preferable one, is illustrated in the accompanying drawings, wherein:—

Figure 1 is a view partly in elevation and partly in section and somewhat diagrammatic in its character, illustrating the system. Fig. 2 is a plan view of the same. Fig. 3 is a detail horizontal sectional view on the line 3—3 of Fig. 1.

Similar reference numerals designate corresponding parts in all the figures of the 25 drawings.

In the embodiment disclosed, an elevated tank or reservoir 4 is employed for holding water or other liquid, and extending downwardly from the bottom thereof, is a fall 30 tube 5, the upper portion of such tube being enlarged, as shown at 6, and provided within the lower portion of the reservoir 4 with a valve seat 7. A vertically movable valve 8 coöperates with the seat, in other words, 35 when elevated, being moved to open position, and when lowered, closing the inlet end of the fall tube 5.

A liquid supplying main in the form of a pipe 9 is provided with a controlling valve 40 10, and above said controlling valve is divided into branches 11 and 12, both of which discharge into the reservoir 4. One of these branches, as 11, is provided with a discharge nozzle 13 that delivers the water against a 45 Pelton wheel or other suitable water motor 14 suitably journaled in a support 15 in the upper portion of the reservoir. This motor, through gearing 16, actuates a rotary cam wheel 17 having a projection 18 on its 50 periphery that operates beneath a collar 19 fixed upon the stem 20 of the valve 8. The other branch 12 of the main 9 has a dis-

charge spout 21 in the reservoir controlled by any well known type of valve 22 that is moved to open position by a projection 23 55 on the swinging arm 24 of a float 25 that rests upon the surface of the liquid in the reservoir, said arm being pivotally mounted, as shown at 26 on the nozzle 21.

Connected to the fall tube 5, adjacent to 60 the enlargement 6, is a vacuum pipe 27, which extends to any or various points within a building or the like, as will be readily understood. This pipe is closed at its lower end, as shown at 28, and at different de- 65 sired points, has branches 29 provided with automatically closing flap valves 30, the said valves being carried by socket pieces 31. These socket pieces are designed to receive the nipple 32 carried by the flexible hose 33 70 of a vacuum cleaner tool 34.

The supply branch 11 is provided with a suitable controlling valve 35, the stem 36 of which is connected to a lever 37 mounted on a bracket arm 38 that is suitably clamped to 75 the pipe branch 11. Secured to this bracket arm 38 is a vacuum chamber 39 that is in communication with the vacuum pipe 27, through the medium of a pipe 40 connected to both. One wall of this vacuum chamber, 80 as shown in Fig. 3, is in the form of a flexible diaphragm 41, and attached thereto is a reciprocating rod 42 that is also pivotally connected to the lever 37. This rod is furthermore attached to a sliding plate 43 85 mounted on the arms of a yoke 44, which surrounds the pipe branch 11. Also slidably mounted on the arms of this yoke, is another plate 45 adjustably maintained in place by nuts 46 screwed upon the said arms, and 90 interposed between the plates 43 and 45, is a coiled spring 47 that surrounds the rod 42.

Briefly described, the operation of the structure is as follows: Assuming the vacuum pipe 27 closed to the outside air, if 95 the valve 10 in the main 9 is opened, water will flow freely through both branches 11 and 12, until a predetermined amount is in the reservoir 4, whereupon the ball 25 will be raised sufficiently to permit the valve 22 100 to close, and thus cut off the discharge of liquid into the reservoir through the branch 12. The branch 11 will also be discharging liquid into said reservoir, but this liquid

will first be projected against the motor wheel 14, causing the same to revolve and thereby, through the gearing, turning the cam 17. The raised portion 18 of said cam 5 will operate against the under side of the collar 19, thereby lifting the valve 8 until said raised portion has passed the collar. As a result, the liquid will flow from the reservoir into the fall tube 5 until the valve 10 8 is released, whereupon it will drop to closed position. This valve, it will be noted, will be intermittently or periodically operated, permitting short "plugs", columns 15 or pistons of water spaced from each other to pass downwardly through the fall tube 5, carrying between them, bodies of air. The only place that this air is supplied from, is the pipe 27, and as a consequence, a partial vacuum will be created in the said 20 pipe 27. It will thus be evident that if a pneumatic tool or other device is attached to said pipe, air will flow therethrough and into the same. In the case of a pneumatic tool, air in a dust-laden condition, will be 25 taken into the tube 5 between the sections or pistons of water and be carried off, the discharge from said pipe 5 being preferably into a sewer. When a predetermined 30 vacuum is secured in the pipe 27, either by the entire closing of said pipe, or by the greater amount of air taken therefrom to that admitted, the diaphragm 41 of the vacuum chamber will be forced inwardly sufficiently to cause the valve 35 to be closed, 35 thus stopping the operation of the motor 14, and consequently permitting the valve 8 to remain in its closed position. The operation therefore is substantially automatic, and in this connection, it may be stated that 40 the projection 18 of the cam 17 is such that it will not stop on a dead center with the valve open. As soon as said projection 18 passes the collar 19, the collar is free to drop, and should it stop at any point on the 45 front rounded surface, the weight of the valve will be sufficient to cause a rearward movement of the cam and motor to insure the closing of the valve.

From the foregoing, it is thought that the 50 construction, operation and many advantages of the herein described invention will be apparent to those skilled in the art, without further description, and it will be understood that various changes in the size, 55 shape, proportion and minor details of construction may be resorted to without departing from the spirit or sacrificing any of the advantages of the invention.

Having thus fully described my invention, 60 what I claim as new, and desire to secure by Letters Patent, is:—

1. In a structure of the character set forth, the combination with a liquid reservoir, of a fall tube leading therefrom, a vacuum

member having communication with the 65 tube, a valve controlling the passage of liquid through the fall tube, means for supplying liquid to the reservoir, and means actuated by the liquid supply for operating the valve. 70

2. In a structure of the character set forth, the combination with a liquid reservoir, of a fall tube leading therefrom, a vacuum member having communication with the tube, a valve controlling the passage of 75 liquid through the fall tube, means for supplying liquid to the reservoir, a motor actuated by the liquid supply, and means operated by the motor for periodically operating the valve. 80

3. In a structure of the character set forth, the combination with a liquid reservoir, of a fall tube leading therefrom, a vacuum pipe connected to the fall tube, a valve at the inlet end of the fall tube, two means for delivering liquid to the reservoir, a float valve controlling one of said means, a motor actuated by the liquid delivered through the other means, a cam member operated by the motor, and a device connected to the valve 90 and periodically actuated by the cam member to periodically open the valve. 95

4. In a structure of the character set forth, the combination with a liquid reservoir, of a fall tube leading therefrom, a vacuum 95 member having communication with the tube, a valve controlling the passage of liquid through the fall tube, means for periodically actuating the valve, and means operated by a predetermined vacuum in the 100 vacuum member for preventing the opening movement of the valve.

5. In a structure of the character set forth, the combination with a liquid reservoir, of a fall tube leading therefrom, a vacuum 105 member having communication with the tube, a valve controlling the passage of liquid through the fall tube, means for supplying liquid to the reservoir, a motor actuated by the liquid supply, means operated by 110 the motor for periodically operating the valve, a valve controlling the liquid supply, and means for closing said valve when there is a predetermined vacuum in the vacuum member. 115

6. In a structure of the character set forth, the combination with a liquid reservoir, of a fall tube dependent therefrom and having a valve seat at its juncture with the reservoir, a valve co-operating with the seat, 120 a motor, a cam member operated by the motor for periodically opening the valve, means for delivering liquid to the reservoir, including a device for directing fluid against the motor to operate the same, a vacuum 125 pipe connected to the fall tube adjacent to the reservoir, a valve in the liquid supply means, a vacuum chamber having a dia-

phragm wall, a connection between the chamber and the vacuum pipe, and means operated by the diaphragm of the vacuum chamber for closing the valve of the liquid supply means when there is a predetermined vacuum in the pipe.

In testimony whereof I have hereunto set

my hand in presence of two subscribing witnesses.

JULIAN N. WALTON.
